S. P. DORKINS.
PLOW ATTACHMENT.
APPLICATION FILED JAN. 5, 1918.

Patented Apr. 8, 1919.

Inventor:

Sam Pintney Dostine,
by ~~W. H. Robinson~~,
Attorney.

UNITED STATES PATENT OFFICE.

SAM PINKNEY DORKINS, OF SALUDA, SOUTH CAROLINA.

PLOW ATTACHMENT.

1,299,435.

Specification of Letters Patent.

Patented Apr. 8, 1919.

Application filed January 5, 1918. Serial No. 210,532.

To all whom it may concern:

Be it known that I, SAM PINKNEY DORKINS, a citizen of the United States, residing at Saluda, in the county of Saluda and State of South Carolina, have invented certain new and useful Improvements in Plow Attachments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to plows. It has for its object to provide a bed or shoe adapted to support a detachable and replaceable plow point or blade, either of the shovel, half shovel, or other type; and also a standard or stock of any suitable approved type so that a relatively light or heavy stock, may be used, as desired, as may be best suited for the particular character of plowing or cultivation to be performed.

For the accomplishment of the foregoing and such other objects as may hereinafter appear, the invention consists in a bed or shoe having features of construction herein-after particularly described and then sought to be clearly defined by the claims, reference being had to the accompanying drawings forming a part hereof, and in which—

Figure 1 is a side view of a plow embodying the invention.

Fig. 2 is a horizontal section on the line 2—2 of Fig. 1.

Fig. 3 is a front view of the bed or shoe;

Fig. 4 is a rear view with the plow point or blade attached and the stock in section;

Fig. 5 is a perspective view of one form of plow point or blade, detached.

In the drawing the numeral 1 designates the face-plate of the bed or shoe which is formed with vertically extending slots 2 and 3 for the reception of a bolt 4 for attachment of a point or blade 5 to the face-plate and to permit vertical adjustment of the point or blade to compensate for its wear.

The bolt 4 also passes through the stock 6 which may be of any approved type, the stock being formed with slots 7 and 8 corresponding to the slots 2 and 3 of the face-plate so that the bolt may be adjusted correspondingly to the adjustment of the plow point or blade, and may be shifted from the

position shown in full lines to the position shown in dotted lines, in Fig. 1, as the plow point or blade wears and is lowered to working position. From the rear of the face-plate extends a landside-plate or wing 9 which is formed in one face with a recess 10 to receive a landside extension plate 11 which has at its upper forward portion an overhanging part 12 which bears against the rear inclined edge of the landside wing 9 so that when the landside extension plate is attached to the landside wing by a bolt 13 the landside extension plate is held rigidly to the landside wing and against any movement relatively thereto. The rear of the face-plate 1 at a point spaced from the landside wing 9 is formed with an enlargement 14 which in conjunction with the landside wing forms a vertical recess or socket 15 which receives the stock 6, and bolts 16 passed through openings in the landside wing, the enlargement 14 and the stock securely hold together the bed or shoe and stock. These means also permit of the ready detachment of the bed or shoe from one stock and attachment to a different stock, one heavier or lighter than the other, to suit the work of cultivation to be performed. For the purpose of affording a retaining or bracing abutment for the plow point or blade, and incidentally affording a wearing surface, a plate or offset 17 is located at the side of the face-plate and landside wing so as to project forward of the face-plate and have the edge of the plow point or blade abut against the same as indicated in the drawing and thus prevent the plow point or blade from turning or twisting on the bolt 4 which attaches it to the face-plate of the bed or shoe. This abutment may be cast integral with the bed or shoe, or attached thereto by the bolts which attach the bed or shoe to the stock.

The attachment bed or shoe described makes it possible to convert one type or style of plow into another by merely substituting one stock for another to suit the conditions to be met with and also to substitute one form of plow point or blade for another by merely removing one from the bed or shoe and substituting another, and also permits the point or blade to be removed and sharpened and replaced as well as to be adjusted to compensate for wear. One bed or shoe therefore answers for different plows and admits of attachment to

many of the different standard types of metal stocks now in use.

Having described my invention and set forth its merits, what I claim is:

- 5 1. A plow blade supporting attachment comprising a bed-plate provided at one side with a rearwardly extending land-side wing and an off-set projecting forward of the bed-plate on the land side, the bed-plate being formed with a socket made in its rear face to receive a plow-stock, the wall of the socket next to the land-side and the opposite wall serving to brace the stock.
- 10 2. A plow blade supporting attachment comprising a bed-plate provided at one side with a rearwardly extending landside wing formed with a recess in one face, a landside

extension-plate having a portion thereof fitting in said recess, and means for securing the extension-plate to the landside wing.

20

3. A plow blade supporting attachment comprising a bed-plate provided at one side with a rearwardly extending landside wing, a landside extension plate having an overhanging portion at its upper edge overlying the upper edge of the landside wing, and means for securing the extension-plate to the landside wing.

25

In testimony whereof I affix my signature in presence of two witnesses.

SAM PINKNEY DORKINS.
